PLASTIC FLY SWATTER

Robert H. Rodgers, Cleveland Heights, Ohio, assignor to
Industrial Plastics, Inc., Cleveland, Ohio, a corporation
of Ohio

Application May 29, 1956, Serial No. 41,699

Term of patent 14 years

(Cl. D31—3)

Fig. 1 is a front elevational view of a plastic fly swatter showing my new design with the handle broken away to represent indeterminate length;

Fig. 2 is a side elevational view thereof; and

Fig. 3 is a top plan view of Fig. 1.

I claim:

The ornamental design for a plastic fly swatter, substantially as shown.
